ELECTRIC SWITCH PLATE

Herman Blau, New York, N. Y.

Application December 20, 1955, Serial No. 39,396

Term of patent 14 years

(Cl. D26—13)

Fig. 1.

Fig. 2.

Fig. 1 is a plan view of a switch plate showing my new design and Fig. 2 is an edge view of the same.

I claim:

The ornamental design for an electric switch plate, substantially as shown.
